(57) **CLAIM**

The ornamental design for a handle for surgical instruments, as shown and described.

DESCRIPTION

FIG. 1 is a rear elevational view of a handle for surgical instruments showing our new design;

FIG. 2 is a front elevational view thereof;

FIG. 3 is a right side elevational view thereof;

FIG. 4 is a left side elevational view thereof;

FIG. 5 is a bottom view thereof;

FIG. 6 is a top view thereof; and,

FIG. 7 is a isometric view thereof showing our design.
